United States Patent Office

Des. 196,196
Patented Sept. 3, 1963

196,196

SATELLITE LOCATOR

Browning E. Marean, Jr., Topsfield, Mass., assignor to
E.I.C. Inc., Boston, Mass., a corporation of Massachusetts

Filed Jan. 3, 1961, Ser. No. 63,422

Term of patent 14 years

(Cl. D52—6)

FIG. 1 is a front elevational view of the satellite locator embodying my new design;

FIG. 2 is a side elevational view thereof;

FIG. 3 is a plan view thereof; and

FIG. 4 is a partial cross sectional view taken on the line 4—4 of FIG. 3.

I claim:

The ornamental design for a satellite locator, as shown.
